BOBBIN FOR SPINNING

Hugo Lampart, Karlsruhe, Germany, assignor to
 Berlin - Karlsruher Industrie - Werke A. - G.,
 Karlsruhe, Germany

Application August 7, 1930, Serial No. 473,703
 In Germany January 3, 1930

3 Claims. (Cl. 242—123)

My invention relates to improvements in bobbins for spinning with beaded edges from any material capable of being rolled, and particularly suitable for the rayon industry. The bobbins 5 or spools of this kind manufactured heretofore were provided with thickened edges or reinforced rims which were more or less hollow and had the defect that the acids and the like used for 10 finishing the bobbins penetrated into the cavities of the edges and thus formed the starting point for oxidation or any other decomposition phenomena of the metal body. Even by careful removal of the acid by washing and otherwise treating the bobbins and in spite of 15 the coating of varnish or lacquer applied later on, it was hitherto impossible to eliminate the detrimental consequences mentioned. Later on 20 also when the bobbins were in use in the spinning process of the artificial silk this coating of varnish did not prevent the entry of acids or stop the decomposition or corrosion at these hollow beadings however carefully they had been closed.

According to my invention this drawback is 25 effectively eliminated by turning the edges over on themselves either inwardly or outwardly and which are pressed together to form jointless solid closed beadings, thickened rims or flanges or reinforced edges.

30 In the drawing affixed to my specification and forming part thereof:—

Figure 1 shows a spinning bobbin in elevation, on a reduced scale,

Figure 2 the inwardly turned over edge of one 35 end of a bobbin according to my invention in cross-section and on an enlarged scale, and

Figure 3 an outwardly turned over edge, likewise in cross-section and on an enlarged scale.

The two ends *x* and *y* of a spinning bobbin or

spool *a*, Fig. 1, are turned over on themselves and pressed together into any desired solid or closed shape, Figs. 2 and 3, so that at the turning over point a joint is merely formed and no cavity. The turning over of the edge may 60 take place either inwardly, as the rim *y* in Fig. 2, or outwardly, as the rim *y'* in Fig. 3.

By my improved bobbin, the penetration or accumulation of substances used in the manufacturing processes, such as acids and the like, at 65 and within the edges of the bobbins is effectively avoided and thus the life of the bobbin extended and any adverse action of the substances on the wound bobbin or spool or any subsequent baths and the like rendered impos- 70 sible.

I claim as my invention:—

1. A metallic spinning bobbin particularly for rayon, comprising a cylindrical shell; and an outwardly-turned beaded rim or edge on each 75 end of the shell, each turned rim bearing tightly against the shell forming a thickened and jointed solid edge to prevent the entry of acids into the joint.

2. A metallic spinning bobbin particularly for rayon, comprising a cylindrical shell; and an inwardly-turned beaded rim or edge on each end of the shell, each turned rim bearing tightly against the shell forming a thickened and jointed solid edge to prevent the entry of acids 80 into the joint.

3. A metallic spinning bobbin particularly for rayon, comprising a cylindrical shell; and a turned beaded rim or edge on each end of the shell, each turned rim bearing tightly against 85 the shell forming a thickened and jointed solid edge to prevent the entry of acids into the joint.

HUGO LAMPART.
